UNITED STATES PATENT OFFICE

165,313

BOTTLE

William Gaston Walkley, Manly, New South Wales, and Walter McEllister Leonard, Neutral Bay, New South Wales, Australia

Application March 29, 1949, Serial No. 1,704

Term of patent 14 years

(Cl. D58—9)

To all whom it may concern:

Be it known that we, William Gaston Walkley, a citizen of the Commonwealth of Australia, residing at King Avenue, Manly, in the State of New South Wales, Commonwealth of Australia, and Walter McEllister Leonard, a citizen of the Commonwealth of Australia, residing at 11a Lower Wycombe Road, Neutral Bay, in the State of New South Wales, Commonwealth of Australia, have invented a new, original, and ornamental Design for a Bottle, of which the following is a specification, reference being had to the accompanying drawing, forming part thereof.

Fig. 1 is a front elevational view of a bottle, showing our new design;

Fig. 2 is a rear elevational view;

Fig. 3 is a side elevational view; and

Fig. 4 is an elevational view of the side opposite to that shown in Fig. 3.

We claim:

The ornamental design for a bottle, as shown.
WILLIAM GASTON WALKLEY.
WALTER McELLISTER LEONARD.
